MINIATURE TOY BASSINET

Evelyn L. Stowell, Garden City, Mich.

Application December 5, 1951, Serial No. 17,607

Term of patent 7 years

(Cl. D34—15)

To all whom it may concern:

Be it known that I, Evelyn L. Stowell, a citizen of the United States, residing at Garden City, Wayne County, State of Michigan, have invented a new, original, and ornamental Design for a Miniature Toy Bassinet, of which the following is a specification, reference being had to the accompanying drawing, forming a part thereof.

Fig. 1 is a perspective view of a miniature toy bassinet, showing my new design; and

Fig. 2 is a rear elevational view thereof.

The scale-like ornamentations on the bottom and on the back of the toy bassinet and the slat-like ornamentations around the top thereof are mere surface markings.

I claim:

The ornamental design for a miniature toy bassinet, substantially as shown and described.

EVELYN L. STOWELL.
